PRODUCE TRAY

Thomas B. Kennedy, Stamford, Conn., assignor to Diamond International Corporation, New York, N.Y., a corporation of Delaware

Filed Feb. 3, 1966, Ser. No. 901

Term of patent 14 years

(Cl. D58—12.6)

FIG. 1 is a view in perspective of the produce tray illustrated in upright position;

FIG. 2 is a view in perspective of the produce tray in inverted position;

FIG. 3 is a top plan view thereof on an enlarged scale;

FIG. 4 is a vertical section taken along line 4—4 of FIG. 3 and looking in the direction of the arrows;

FIG. 5 is a vertical section taken along line 5—5 of FIG. 3 and looking in the direction of the arrows; and

FIG. 6 is a further enlarged fragmentary vertical section taken along line 6—6 of FIG. 3.

I claim:

The ornamental design for a produce tray, as shown.
